STORM PROTECTION WINDOW BRACE

Harold R. Carney, Houston, Tex.

Application November 21, 1947, Serial No. 787,345

5 Claims. (Cl. 189—78)

1

The invention relates to a storm protection window brace and to a method of easily and efficiently installing window braces on show case windows, large residential windows, and any type of window which is likely to be shattered in a storm or hurricane, and it also relates to a window comprising window braces as a part thereof.

An object of this invention is to provide a window brace which can be rapidly installed on the frames of the windows to be protected by fixing the brace to the window frames by means of screws which thread into previously prepared holes in the frames.

Another object of this invention is to provide a window brace which consists of separate sections which can be so spaced inwardly and outwardly of the glassed portion of a window that the glass is braced after the pattern of a checker board or grillage.

A further object of this invention is to provide a window brace consisting of separate sections of this kind in which structural members, as steel channels, which are fixed to the window frame, have underlying therebeneath vibration dampening and translating elements such as rectangular rubber strips which are in surface contact with the window glass.

Yet another object of this invention is to provide a window braced against storms by cross-bracing the window on either side of the window glass with inter-crossing elements having rubber strips therebeneath, the elements on the outside and inside of the window complementing each other in a way to subdivide the window glass into a checker board of reinforced areas, the substantially checker-boarded pattern being obtained by extending the elements either rectangularly to the window frames sides, or at an angle thereto, as diagonally.

Still a further object of this invention is to provide window braces having sections composed of inter-crossing members so arranged as to complement each other from opposite sides of the window glass which is to be braced so that the effect of vibratory stresses and strains set up in the window glass during storms and hurricanes may be localized to small areas of the glass surface.

Other and further objects of this invention will be apparent from the following description taken in connection with the drawing in which:

Fig. 1 is an elevation of a window which shows two cross-bracing sections on the outside of the window complemented by one cross-bracing section on the inside thereof.

Fig. 2 is a cross-section of the window and of the cross-bracing sections taken along line 2—2 of Fig. 1.

Fig. 3 is a sectional elevation showing a fragmentary section of a window and of the window

braces of this invention which shows a method of mounting them to brace a show case window in a building having concrete walls and wooden floors.

5 Fig. 4 is a fragmentary cross-sectional view which shows how the rubber strips beneath the structural members of the braces may be offset by notching out, or by the compressibility of the rubber itself, so as to compensate for the divisional strip between panes of glass.

In Fig. 1 of the drawings a window frame 1 has two cross braces 2 and 3 mounted on the outside of the vertical sides 4 of the window by means of screws 5. These two cross-brace sections 2 and 3 are complemented by one cross-brace section which is located in spaced relationship on the inside of the window and which is mounted to the vertical sides of the window by means of screws 5, not shown. It is noticeable 15 that in this arrangement the outside cross-brace sections have one structural member 6, which extends horizontally, and two intercrossing members 7, which extend vertically, whereas the cross-bracing member on the inside of the window 20 pane 22 comprises a cross-bracing section 8 which consists of one horizontally extending member 9 and one vertically extending member 10.

25 Referring to Fig. 2, the cross-bracing sections are shown to consist of channels 6, 7, 9 and 10 which have underlying therebeneath rectangular sectioned rubber strips 11 and 12 which are affixed to the webs of the channels in any well-known manner, such as by gluing.

30 Fig. 3 shows in detail one method of mounting the cross-bracing sections of this invention on a show case window and in this view a wood screw 20 passes through an angular foot 13, then through the floor board 14 into a floor joist or underlying support 15. The vertically extending

35 members 7 of the outside cross-bracing sections are shown as being mounted in the concrete wall of the building by means of a bolt 16 which extends through the vertically extending member 7 and is threaded into a nut 17 which is cemented 40 in place in a counterbored hole 18 in the concrete wall.

45 In Fig. 4 a rectangular rubber strip 11 is shown as offset to compensate for the wooden or steel strip 23 which constitutes the division between panes 21 in windows which are not comprised of a single glass plate. This offset can result from the mere compression of the rubber strip in cases where the texture of the rubber strips employed admit of such compressibility. In constructions where a harder, less compressible rubber strip may be used, division strip 23 may be compensated for by notching out the rubber strip to the necessary shape.

50 The arrangement of the cross-bracing sections of this invention is not limited to the illustrative

structures shown in Fig. 1 and it is conceivable that it may be advantageous to reverse the installation of outer and inner cross-bracing sections to meet varying designs of windows. It may also be advantageous to have additional vertically extending members and additional horizontally extending members in each cross-bracing section. The invention is not to be limited to the methods of mounting shown in Fig. 3 but this invention is drawn to take in any practical method of mounting cross-bracing sections arranged after the general pattern thereof.

It is pointed out that the construction of Fig. 1, in which the vertically extending member 10 of the inside section extends only slightly beyond the horizontally extending outside members, is a construction adaptable to cases where the horizontal window frame sides 19 may be relied upon to especially reinforce the glass areas adjacent thereto. In other cases it may be advantageous to extend the member 10 to terminate on a line parallel with the members 7 to sufficiently reinforce the glass and to form a substantially uniformly checker boarded pattern.

It is further pointed out that the construction of Fig. 1 may be varied so that the vertical cross-bracing members 7 and 10 extend to be connected to the window frame in the same manner as the horizontally extending members are connected.

Notice should also be taken of the fact that any of the cross-bracing structures disclosed, and any of the variations thereof described, may be assembled with a window as an integral part thereof, and in such instances more permanent connections to the window frame can be made in any number of well known ways without departing from the substance and theory of this invention.

Broadly, this invention has as a general object the employment of variously arranged cross-bracing sections consisting of intercrossing structural members which have underlying therebeneath vibration dampening and distributing rubber strips, the overall cross-bracing arrangement being designed to distribute and dampen the vibratory stresses and strains which hurricanes, storms and high winds may set up in window glass, and to localize these undesirable forces into small rectangular surface areas of glass. In addition, the structure and method of this invention not only considers the cross-bracing elements, but it also considers a window having these elements as a part thereof and it further considers the method of constructing a window braced with these elements.

It is therefore obvious that the specific construction which has been described is only illustrative of one embodiment of the invention and it is thereby understood that the invention is not confined to such construction but broadly comprehends the means and methods of cross-bracing windows within the material structures and general spirit of this invention, the structural pattern thereof being obtained by extending the elements either rectangularly to the window frames sides, or at an angle thereto, as diagonally.

What is claimed is:

1. A storm protection braced window comprising a frame supporting glass thereinbetween, a plurality of inter-crossing structural members having rubber strips attached beneath each member and extending substantially co-extensive with the length thereof and in contact with the

window glass, said members being connected to opposite sides of said frame so that a glass area unreinforced on one side has centrally thereof on the opposite side the inter-crossed center of a structural member.

2. In a storm protection window brace for a window comprising a frame supporting glass thereinbetween, the combination of, a plurality of inter-crossing structural members having rubber strips attached beneath each member and extending substantially co-extensive with the length thereof and in contact with the window glass, said members being in complementary spaced relationship on alternate sides of the window glass from each other so as to strengthen the window glass and dampen vibrations occurring therein by subdividing the window brace into a substantially checker-boarded pattern of re-inforced areas.

3. In a storm protection window brace for a window comprising a frame supporting glass panes thereinbetween, the combination of a plurality of inter-crossing structural members having rubber strips attached beneath each member and extending substantially co-extensive with the length thereof and in contact with the paned window glass, said members being connected to opposite sides of said frame so that a glass area unreinforced on one side has centrally thereof on the opposite side the inter-crossed center of a structural member, said rubber strips being adapted to fit over the division between panes.

4. In a storm protection window brace for a window comprising a frame supporting glass thereinbetween and adapted to be installed within a frame encasing building structure, the combination of, a plurality of inter-crossing structural members having rubber strips attached beneath each member and extending substantially co-extensive with the length thereof and in contact with the window glass, said members being adapted to complementarily re-inforce the window glass from opposite sides thereof, and means connected to said members for attaching the braced window to the frame encasing building structure.

5. A window comprising, a window frame adapted to be installed within a frame encasing building structure, a paned window glass, and a plurality of inter-crossing structural members having rubber strips attached beneath each member and extending substantially co-extensive with the length thereof and in contact with the window glass, said members being adapted to complementarily re-inforce the window glass from opposite sides thereof, and means connected to said members for attaching the braced window frame to the frame encasing building structure.
